US00D800758S

(12) **United States Design Patent** (10) Patent No.: **US D800,758 S**
Hess et al. (45) Date of Patent: **** Oct. 24, 2017**

(54) **COMPUTER DISPLAY SCREEN WITH GRAPHICAL USER INTERFACE FOR LIGHTING**

(71) Applicant: **Seasonal Specialties, LLC**, Eden Prairie, MN (US)

(72) Inventors: **Tim Hess**, St. Louis Park, MN (US); **Christine Werner**, St. Louis Park, MN (US); **Steven Altamura**, Scarsdale, NY (US); **Derek Anderson**, Blaine, MN (US)

(73) Assignee: **Seasonal Specialties, LLC**, Eden Prairie, MN (US)

(**) Term: **15 Years**

(21) Appl. No.: **29/600,099**

(22) Filed: **Apr. 10, 2017**

Related U.S. Application Data

(62) Division of application No. 29/503,069, filed on Sep. 23, 2014.
